Patented Sept. 26, 1967

208,693

EARTH MOVING MACHINE

Derek A. Prime, Doveridge, England, assignor to J. C. Bamford (Excavators) Limited, Rocester, England, a British company

Filed Apr. 14, 1966, Ser. No. 1,894

Claims priority, application Great Britain Feb. 24, 1966

Term of patent 14 years

(Cl. D14—3)

Fig. 4.

Fig. 2.

Fig. 3.

Fig. 5.

FIGURE 1 is a side elevation of an earth moving machine showing my new design.

FIGURE 2 is a top plan view of the earth moving machine shown in FIGURE 1.

FIGURE 3 is a rear elevation of the earth moving machine shown in FIGURE 1.

FIGURE 4 is a front elevation of the earth moving machine shown in FIGURE 1.

FIGURE 5 is a side elevation of the earth moving machine shown in FIGURE 1, taken from the other side of the machine to the elevation shown in FIGURE 1.

The dominant features reside in the solid line portions.

I claim:

The ornamental design for an earth moving machine, substantially as shown and described.
